UNITED STATES PATENT OFFICE

2,193,200

CURTAIN HANGING FIXTURE

Nicholas Menutole, Winthrop, Mass.

Application May 10, 1939, Serial No. 272,801

3 Claims. (Cl. 248—265)

My present invention relates to curtain fixtures, and more particularly to an improved curtain hanging fixture which provides a vertical adjustment of the curtain rods enabling the housewife to demount and mount the assembled curtain and rod without climbing on ladders, chairs or other articles in order to reach the high window fixture over which the curtain rods are attached.

10 The principal object of my invention is an improved curtain hanging fixture;

Another object is an improved curtain hanging fixture which can be easily raised or lowered from the floor for the purpose of attaching the curtain rod;

Still another object is an improved curtain hanging fixture which provides for adjustment in a vertical plane for the holes in the conventional fixture to which the curtain rods are attached;

A still further object is an improved curtain hanging fixture of the class above described which when in place presents a smooth plain surface and protected track which cannot be clogged with paint, varnish or the like, and

Other objects comprising the construction and operation of my improved apparatus will be apparent, as the description of the same progresses.

In the drawing illustrating the preferred embodiment of my invention,

Fig. 1 is a front elevation of the preferred embodiment of the device, the window finish at the top and bottom being broken away;

Fig. 2 is a fragmentary cross-section taken on the lines 2—2 of Fig. 1;

Fig. 3 is a modification of the device shown in Fig. 1;

Fig. 4 is a fragmentary cross-section taken on the line 4—4 of Fig. 3;

Fig. 5 is fragmentary cross-section taken on the lines 5—5 of Fig. 1;

Fig. 6 is a fragmentary cross-section taken on the lines 6—6 of Fig. 3;

Fig. 7 is a fragmentary cross-section of the lower end of the fixture when in a raised and locked position, as shown in Figs. 1 and 3, and

Fig. 8 is a fragmentary detail elevation of the upper portion of the apparatus and left-hand corner of the window showing a modification of the curtain rod attachment.

In the cross-sections shown in Figs. 2 and 4, the fixture has been lowered part way down from the positions shown in Figs. 1 and 3 to better show the action of the apparatus.

55 10 indicates the header portion of the window

finish and 11 the vertical side strip leading down from the header 10.

The preferred form shown in Fig. 1 comprises two flat tubular members 12 and 13 both of which are open on a portion of one side, as shown in Figs. 2 and 5. The back member 13 is attached at 14 to the header 10, and at 15 to the lower portion of the window finish strip 11. It will be noted that the members 12 and 13 are telescoped together in an opposite manner so that the openings in the sides are covered by the solid side of the other member. In the relation shown in Figs. 1 and 2, the outer member 13 presents a plain solid surface when in place, as shown in Fig. 1. The purpose of this arrangement is to prevent the members 12 and 13 from becoming stuck together by paint or varnish when redecorating of a room is going on. Also by such an arrangement, the fixture may be painted or varnished together with the woodwork without causing any damage to the fixture. Of course when such decorating is done the fixture should always be in the raised position shown in Fig. 1.

Adjacent the top of the outside member 12, I have located a vertical slot 16 in which the bolt 17 may be adjusted to accommodate the curtain rod receiving member 18 which is provided with the rod hooks 19. The bolt 20 is permanently fixed through a hole 20a provided in the member 12. The member 18 is a conventional curtain rod fixture but the attaching holes vary somewhat in different makes but with the elongated slot 16 in the upper portion of the outer member 12 all sizes are accommodated easily. Once this adjustment is made the member 18 is solidly fixed to the outer member 12.

When it is desired to lower the curtain, the outer member 12 is pulled down by means of the knob 21 until the member 18 approximates the position indicated in dot-and-dash lines at the lower portion of Fig. 1 and the curtain rod is removed or mounted, as the case may be, on the hooks 19.

The member 12 is maintained in an upper position by means of the concaved surface of the back of the knob 21, as indicated at 22, which slips over the head of the screw 23 and which anchors the lower portion of member 13 to the woodwork 11.

At Fig. 8, I have shown a modification of the member 18, as indicated at 24. This is a flat plate which is provided with a hole 25 and elongated slot 26 on its free end and which is adapted to adjustably receive other types of fixtures. The member 18 may also be mounted on

the extension member 24 if desired. Any other similar curtain rod receiving member may be used if desired.

In my modified form shown in Figs. 3, 4 and 6, 5 the members 12 and 13 are reversed in their assembled form, as indicated at 12a and 13a. In this relation the member 12a becomes the fixed member attached to the header 10 and finish strip 11 and the slot 16a is placed in the 10 outer face of the sliding member 13a. A fixture like 18 is applied in the same manner excepting that a small spacing washer or the like 27 is used to bring the member 18 out over the curved edges of the member 12a. The same extension 15 member 24 may be substituted for the member 18 without change. The same knob 21 and concaved member 22 is also used without change.

The operation of this modified form is the same as in the preferred form excepting that 20 it will stick together if painted or varnished on its outer surface where the opening occurs in the member 12a. In the preferred form this portion of the fixture is hidden and it is never necessary to paint this portion, and no care is 25 necessary when working a brush in back of it on the woodwork.

The drawing illustrating the telescoped members is somewhat exaggerated as to the thickness of the material in interest of clarity of showing. 30 Actually the metal is much thinner in proportion to the width of the tube, and due to the reversed telescoped arrangement of the pieces, the strength is very greatly increased such that it very nearly approaches the rigidity of a perfect tube.

35 Having thus described my invention, what I claim as new is:

1. A curtain hanging fixture comprising in combination, a pair of flattened tubular members one telescoped within the other and each having 40 a longitudinal gap extending from one end to the other, one of said tubular members having a

longitudinal slot and bolt hole adjacent the upper end, a curtain rod receiving member attached to the upper portion and through said slot and bolt hole in said tubular member, means for attaching said other tubular member to the side of a window 5 opening.

2. A curtain hanging fixture comprising in combination, a pair of flattened tubular members one telescoped within the other and each having a longitudinal gap extending from one end to the other, the said gaps of said tubular members being positioned opposite to each other when said tubular members are telescoped together, one of said tubular members having a vertical slot and bolt hole adjacent one end, extension means 15 located on each end of one of said tubular members and screws adapted to mount said fixture on the side finish of a window, a concaved member located on the inside of the lower portion 20 of one of said tubular members, said concaved member being adapted to engage over the head of one of said screws when said tubular members are telescoped together.

3. A curtain hanging fixture comprising in combination, a pair of flattened tubular members one telescoped within the other and each having a longitudinal gap extending from one end to the other, the said gaps of said tubular members being positioned opposite to each other when 30 said tubular members are telescoped together, extension portions on one of said tubular members and anchor members adapted to attach said member to the finish strip of a window, a recessed member located on the inside of one 35 of said tubular members and adapted to lock over the lower anchor member of said attached tubular member when said members are telescoped together, means for mounting a curtain rod receiving member to one of said tubular 40 members.

NICHOLAS MENUTOLE.
